(57) **CLAIM**

The ornamental design for a toy for domestic pet as shown and described.

DESCRIPTION

FIG. 1 is a perspective view of a toy for domestic pet showing our new design.

FIG. 2 is a front elevation view of thereof.

FIG. 3 is a rear elevation view thereof.

FIG. 4 is a top plan view thereof.

FIG. 5 is a bottom plan view thereof.

FIG. 6 is a left side elevation view thereof; and,

FIG. 7 is a right side elevation view thereof.

The dashed lines shown in the drawings are for purposes of illustrating portions of the toy for domestic pet that form no part of the claimed design.

1 Claim, 7 Drawing Sheets
